UNITED STATES PATENT OFFICE.

WILLIAM SCHILDWACHTER, OF WALWORTH, NEBRASKA.

WELL-TOOL.

1,087,262.

Specification of Letters Patent. Patented Feb. 17, 1914.

Application filed February 6, 1913. Serial No. 746,825.

To all whom it may concern:

Be it known that I, WILLIAM SCHILDWACHTER, a citizen of the United States, residing at Walworth, in the county of Custer, State of Nebraska, have invented certain new and useful Improvements in Well-Tools; and I do hereby declare the following to be a full, clear, and exact description of the invention, such as will enable others skilled in the art to which it appertains to make and use the same.

This invention relates to well tools adapted to remove broken pump rods from deep well casings and has for an object to provide a tool which will effectively engage and remove various sizes of metal and wood pump rods.

A further object of the invention is to provide a tool having novel jaws for securely holding pump rods to enable the same to be unscrewed at the joints and removed in sections.

With the above objects in view the invention consists of certain novel details of construction and combination of parts herein-after fully described and claimed, it being understood that various modifications may be made in the minor details of construction within the scope of the appended claim.

In the accompanying drawings illustrating this invention:—Figure 1 is a side elevation. Fig. 2 is a longitudinal section with the jaws dotted in operative position. Fig. 3 is a cross section on line 3—3 Fig. 2. Fig. 4 is a detail perspective view of the stationary jaw. Fig. 5 is a detail perspective view of the movable jaw. Fig. 6 is a longitudinal section of a modified form for removing wooden pump rods. Fig. 7 is a cross section on line 7—7 Fig. 6. Fig. 8 is a detail perspective view of the movable jaw shown in Fig. 6.

Referring now to the drawings in which like characters of reference designate similar parts, the tool is shown to comprise a cylindrical casing 10 having a reduced upper end 11 and having the bore near the lower end tapered to a lower feather edge 12. The casing is formed in one side with a pair of vertically aligned slots 13 and 14.

Within the casing diametrically opposite the slots and in registration with the lower slot 13 is a fixed jaw 15 formed of a curved plate which is removably secured to the casing by means of screws 16 or otherwise, and

is formed on the inner face with upwardly projecting teeth 17.

A movable jaw 18 formed from a curved plate is slidably mounted within the casing diametrically opposite the fixed jaw and is provided on the outer face with spaced substantially triangular cam projections 19 and 20 which extend through the slots 13 and 14 respectively, the outer inclined cam surfaces of the projection riding upon the bottom edges of the slots when the jaw is slid downwardly and forcing the jaw inwardly in the direction of the fixed jaw. The jaw is provided with a stem 21 which projects axially through the reduced end 11 of the casing and forms means for manually moving the jaw. The jaw is provided on the inner face with upwardly projecting teeth 22 and is provided on the outer face with a stop lug 23 adapted to engage with the upper edge 75 of the lower slot 13 and limit upward movement of the jaw.

To prevent rotation of the movable jaw in the casing a pair of opposite stop strips 24 and 25 are fixedly secured in the casing by rivets 26 or otherwise, each strip being substantially wedge-shaped in cross section as shown in Fig. 3 and bearing with its inner flat face against the adjacent end edge of the movable jaw whereby the jaw is free to move inwardly between the strips but is positively held against rotation in the casing.

A frusto-conical interior guide 27 is snugly fitted in the lower end of the casing and is removably secured thereto by means of a screw 28 or otherwise. The guide is formed with a tapered bore 29 which is of sufficient diameter at the upper end to align with the working faces of the fixed and movable jaws and flares outwardly toward the lower end to a feather lower edge 30 which is flush with the feather lower edge of the casing. This guide directs the pump rod truly into the space between the fixed and movable jaws.

The movable jaw is normally disposed at its upper limit of movement with the stop lug 23 in contact with the upper edge of the lower slot 13. The casing is let down into the deep well, and as will presently be described is guided during such movement so that the pump rod passes into the interior guide 27 and lodges between the working faces of the fixed and movable jaws. The

stem of the movable jaw is now tapped to move the movable jaw downward whereupon the cam projections simultaneously move the jaw inward with a resultant tight clamping of the pump rod to the fixed jaw. The casing may now be raised from the well to withdraw the pump rod, or in case there are joints in the pump rod to be unscrewed, the casing may first be rotated to unscrew the joint before removal of the rod may be effected.

For guiding the casing 10 down into deep well casings of various diameters so as to center the inner guide 27 relatively to the pump rod which it is desired to remove, I provide exterior guide sleeves 32, 33 and 34 which telescope one within the other and surround the lower end of the casing 10. The inner sleeve 32 is removably fixed to the casing by set screws 32' or otherwise; the intermediate sleeve 33 is removably fixed to the inner sleeve by set screws 33' or otherwise; and the outer sleeve 34 is removably fixed to the intermediate sleeve by set screws 34' or otherwise. The bores 35, 36 and 37 of the sleeves flare outwardly and merge into each other to produce a conical guide wall as clearly shown in Fig. 2.

In use the outer guide sleeve 34 will snugly fit the bore of a relatively large well casing and hold the tool casing 10 centered in the well casing while the flared bore of the sleeve will take up the upper end of the pump rod should it be lying against the wall of the well casing and direct the same into the inner guide sleeve 27. Upon the outer sleeve 34 being removed, entry of the tool casing 10 into a well casing of medium diameter is facilitated. When the well casing is of small diameter the inner sleeve 32 is removed as the tool casing 10 itself is formed of sufficient diameter to fit the bore of a small pump casing.

For removing wood pump rods the movable jaw, stationary jaw, and interior guide above described are removed and a movable jaw 38 such as is shown in Figs. 6 to 8 inclusive is substituted. The movable jaw in this instance is formed of a plate having a single transverse upwardly projecting sharpened tooth 39 on the inner face near the lower end and having on the outer face near the lower end a substantially triangular cam projection 40 which engages with the

lower edge of the lower slot 13 and forces 55 the tooth to penetrate and thus obtain a firm grip on the small pump rod as well as clamping the same to the inner face of the casing. To limit movement of the jaw a stop lug 41 is fixed to the outer face of the jaw and engages with the upper edge of the lower slot. The jaw is equipped with a stem 42 which projects through the reduced end of the casing 10 and forms means for actuating the jaw as above described.

It is to be understood that any desired number of outer guide sleeves may be employed to promote the effective operation of the tool as also may any desired number of different sizes of interior guides, without departing from the spirit or sacrificing any of the advantages of the invention. Furthermore, a leather or similar packing strip 43 may be inserted back of the fixed jaw to space the latter from the casing in order to facilitate the most effective working of the tool.

What is claimed, is:—

A well tool including a cylindrical casing having a reduced upper end and having the lower edge tapered internally to a feather edge to provide a guide surface, a jaw actuating rod projecting down through said reduced upper end and being offset at the lower end to ride along the side of said casing, a jaw integral with the offset end of said rod and having outwardly directed cam projections extending outwardly through slots in the side of said casing, a fixed jaw removably secured in said casing opposite the first named jaw, a pair of opposite wedge-shaped plates removably secured to said casing between the edges of the first named jaw and said fixed jaw and having their opposing faces flat whereby to positively prevent rotation of the first named jaw when being actuated by said rod, and a removable flared guide sleeve on the lower end of said casing having the inner surface forming a continuation of the tapered inner surface of said casing.

In testimony whereof, I affix my signature, in the presence of two witnesses.

WILLIAM SCHILDWACHTER.
